MACHINE GUN FIRE CONTROL APPARATUS

George Edward Beharrell, Streetly, Joseph Wright, Coventry, and Henry Trevaskis, Sutton Coldfield, England, assignors to Dunlop Rubber Company, Limited, London, England, a British Company

Application March 12, 1936, Serial No. 68,404
In Great Britain March 6, 1935

7 Claims. (Cl. 89—27)

This invention concerns apparatus for operating machine guns of the kind in which the working mechanism of the gun itself comprises a recoiling breech block which is initially displaced to supply the energy required to load and/or fire the first shot and in which the energy required to discharge a series of rounds subsequent thereto is derived from the energy of recoil consequent upon the initial and each of 5 the successive discharges.

In particular the invention is designed to operate machine guns of the kind in which the recoiling breech block is displaced from an initial position to an intermediate safety position from 15 which it returns to the initial position thereby rendering the gun ready to be fired.

By incorporating the apparatus described below, each gun may be placed in the most favorable position, and so that one or more rounds 20 may be fixed thereby without necessitating the immediate proximity of the gunner.

Such remote fire control is particularly advantageous in aircraft as it enables several guns to be located far apart on the wings and/or in 25 other positions and enables such guns to be fired without regard to the airscrew, by one person alone.

According to this invention, in rapid firing small arms of the kind having a recoiling breech block and a gun firing trigger or button, we provide pneumatic operating means comprising a compressed air supply connected to a trigger motor comprising a cylinder and piston, which piston is displaceable into contact with the said 30 trigger or button by the operation of a valve interposed between the said motor and the said air supply.

In order that the invention may be more easily understood and readily carried into effect, the 40 same will now be described with reference to the accompanying drawings in which:—

Fig. 1 is a diagrammatic representation of the general arrangement of the pneumatic operating means including the pipe circuits; Fig. 2 is a part 45 sectional side elevation of the chief flying control, and valve mechanism operated therefrom; Fig. 3 is a side elevation of the pneumatic safety cocking mechanism; Fig. 4 is a part sectional plan view of the cocking mechanism shown in 50 Fig. 3; and Fig. 5 is a part sectional side elevation of the spring loaded gun trigger actuating piston and cylinder.

Fig. 6 is a view similar to that of Fig. 3 of a different embodiment of certain parts of the invention.

In the general arrangement shown diagrammatically in Fig. 1 compressed air is carried in a container 1 from which the air supply is released to two pipes 2 and 3.

The pipe 2 transmits air under pressure to the valve casing 4 carried by the chief flying control and when this valve is opened the air passes on through the pipe 5 to the cylinder of the trigger motor 6, the piston 7 of which is expelled to press upon the firing trigger or button 8 of the gun 9.

The valve in the casing 4 is opened and shut by the movement of a firing control in the form of a lever 10 carried by the chief flying control 11.

The other pipe 3 referred to above transmits air under pressure to two valve mechanisms 15 operated individually by push buttons 12 and 13 which may be positioned on the dashboard or fuselage 14 in front of the chief flying control 11.

Depression of the push button 13 admits air under pressure to the pipe 15 by which it is transmitted to the loading cylinder 16, the piston rod 17 of which is expelled thereby into contact with a member 18 forming part of and projecting from 25 the internal recoiling loading mechanism of the gun 9.

The other push button 12 when depressed admits air under pressure from the pipe 3 connected to the container 1 to a pipe 19 connected to a cylinder 20, the piston 21 of which is thereby expelled to contact the toe 22 of a catch rocking upon a fork carried by the end of the piston rod 17.

The internal loading and recoil mechanism of 35 the gun which is not shown is operated by the forward and backward movement of an internal recoiling breech having an actuating member 18 projecting from the casing 9 enclosing the gun.

Beneath the casing 9 is a supporting frame, 40 part of which is shown in outline at 23, this casing containing and positioning the cylinders 16 and 20 operating the loading and recoiling breech block member 18 which is displaceable from the initial position shown in dotted lines in Fig. 3 45 to an intermediate position shown in solid lines whence it is returned to the initial position thereby loading the gun in readiness to fire one or a succession of rounds of ammunition.

The displaceable recoiling breech member 18 50 is displaced from its initial position adjacent the larger cylinder 16 by engagement of a toe portion 24 formed on the member with a recess 25 formed on a rocking detent 26 which is pivoted at 29 between the forked end 27 of the piston 55

rod 17 connected to the piston 28 within the cylinder 16.

At the end of its outward stroke the recoiling breech member 18 is carried to a position shown in full lines in which the toe of the catch 22 on the lower portion of the forward end of the detent momentarily overrides a trip catch 30 which is maintained in the position shown by a spring 31.

0 The recoiling breech block is thereby held in an intermediate safety position in which the operation of loading has not been fully completed.

In the construction shown the loading operation is completed by the release of the catch 22 5 from the trip 30.

An upwardly extending contact 32 forming part of the rocking detent 26 is struck backwards by the piston 21 which is driven out of the cylinder 20 by the admission of fluid pressure 10 through the pipe 19 admission of air to which is controlled by the valve operated by the press button 12, Fig. 1.

Alternatively, however, the automatic retention of the breech recoil member 18 in this intermediate safety position which is obtained as described above may be dispensed with if desired by a modification of the construction shown.

Essentially this modification consists in replacing the cylinder 20 and piston 21 with an 30 abutment placed in a position corresponding to that occupied by the piston 21 when expelled from the cylinder. The parts 31, 30 and 22 may also be dispensed with in this case.

In consequence the contact 32 strikes the abutment and the recoil member 18 returns immediately to the initial position under the influence of the return coil springs of the gun mechanism not shown.

In either case the recoiling breech member 40 18 returns to the initial position entirely unimpeded by the detent 26 and its supporting fork and piston rod 17 whether one round or a succession of rounds are fired from the gun.

The coil springs 33 which retract the piston 17 45 to its initial position are secured at one end to the pivot spindle 29 upon which the detent 26 rocks and at the other to abutments 34 extending across the base of the cylinder 16.

On its return under spring pressure as described above, the inclined reverse face of the 50 projecting contact 32 strikes the faces of a pair of studs 48, Fig. 4 whereby the contact 32 and in consequence the catch 22, are depressed downwardly to the position shown in dotted lines thereby raising the recessed portion 25 to the initial position shown in dotted lines in readiness 55 to engage the breech recoiling and loading member 18.

The end of the detent 26 adjacent the cylinder 60 16 has a toe portion 35 which in rising contacts the under surface of the fork to position the detent in readiness for the next outward stroke of the piston 17.

The recessed shoulder 25 which engages the 65 breech recoil member 18 is initially spaced therefrom in the direction of the cylinder 16 which prevents the detent being raised to the initial position by striking the contacts 48 which would impede the movement of the recoiling member 18 70 should reciprocation of this member take place during the spring loaded movement of the piston and detent to the initial position.

The admission of compressed air from the 75 container 1 to the larger cylinder 16 through the pipe 15 is effected by depressing the push button

13 to unseat a spring loaded non-return valve of any suitable type, air is similarly admitted to the small cylinder 20 through a similar valve operated by the push button 12, but as described above, the cylinder 20 and piston 21 together 5 with the pipe 19 and push button 12 may be dispensed with if desired.

Instead of a pneumatically operated piston a firing block 21' may be positioned, as shown in Fig. 6 and may be provided fixed in the position 10 occupied by the piston 21 when actuated so that as the contact 32 reaches it it tilts the catches 25 and 22 in a manner similar to that caused by the displacement of the piston.

The firing button or trigger of the gun itself 15 is shown diagrammatically at 8 in the form of a button projecting from an aperture in the gun housing 9, Fig. 1.

The trigger or firing button of the gun is actuated by a firing control which in the construction shown takes the form of a finger lever 10 which in the case of a gun on an aircraft may be mounted on the control ring handle 11 of the chief flying control so that the gun is aimed and fired at the target by directing the aircraft itself 25 in the direction of the target.

If desired two or more such firing levers may be positioned side by side upon the chief flying control to permit of firing several guns or groups 30 of guns at the same time.

One such firing control lever is shown in Fig. 2 pivoted to the base of the spade grip at 37 and having a forwardly directed toe portion 38 which on movement of the lever from the dotted line position to the operating position shown in full 35 lines pushes down a connection 39, the base 40 of which depresses a cylinder 41 loaded by a spring 42 upon an apertured washer 43 of yielding material such as rubber.

The compression of the washer 43 seals an air 40 chamber beneath it and permits the base of the cylinder 41 to contact and downwardly to displace the valve spindle 44 which carries with it the seating portion 45 thereby separating the said seating portion from its fixed coating tubular conical 45 portion 46.

Air under pressure is thereby admitted from the container 1 into the chamber, the upper end of which is temporarily sealed by compression of the washer 43 and passes through slots 36 and 50 annular ports 47 into the outlet pipe 5.

The outlet pipe 5 is connected to the cylinder 6, Fig. 1 of the gun trigger actuating motor, the piston 7 of which is expelled into operative contact with the gun trigger or button 8. 55

On releasing the finger lever 10 the pressure on the washer 43 is relieved and the seating portion 45 of the valve returns to its seat thereby cutting off further supply of compressed air from the container 1.

The air pressure in the pipe 5 and port 47 is then reduced to atmosphere by exhausting through the aperture in the resilient washer 43 whereupon the spring 48 in the trigger motor 6 returns the piston 7 to its initial position and 65 relieves the pressure on the gun trigger 8.

In the operation of the apparatus described above, the operator presses the button 13 whereupon air is admitted through the pipe 15 behind the piston 28 of the cylinder 16. 70

The piston 28 and its rod 29 move outwardly of the cylinder and the portion 25 of the detent 26 engages the recoiling breech member 18 and carries it to the outer limit of its stroke.

In this intermediate safety position the recoil 75

member 18 may either be detained or immediately released as described previously.

In the former case release is consequent upon operation of the button 12 which displaces a valve to release air from the container through the pipe 19 to displace the piston 21 which strikes the rounded contact portion 32 of the detent 26.

The interlocked catches 30 and 22 are thereby separated and the piston rod 17 is returned to its initial position by the springs 33, while the recoiling breech member 18 is returned by the internal mechanism of the gun.

In its return the detent 32 strikes the stud contacts 48 which return the detent to its initial position.

The gun having been loaded by the above operations depression of the firing lever 10 fires the gun by unseating the valve disc 45 to admit air from the container 1 to the cylinder 6, the piston 20 of which depresses the gun firing button or trigger 8.

The operation of the apparatus is briefly as follows:—

Starting from a position shown in Fig. 1 and indicated at dotted lines in Fig. 3, the valve 13 is opened admitting air through the pipe 15 to the right hand end of the cylinder 16. This forces the piston 28 to the left carrying with it the piston rod 17 and detent 25. The detent 25 engages and moves the depending arm 18 of the breech block. When the piston 28 reaches the end of its stroke the catch 22 engages the latch 30 and is held in its extended position. Upon opening the valve 12, air flows from the reservoir 35 through the pipes 18 and 19 to the cylinder 20, pushing the piston 21 outwardly against the upwardly projecting finger 32 of the catch, first swinging the part 25 to release the breech block arm 18 so that it may return to its original position shown in dotted line in Fig. 3, and then releasing the catch 22 from the latch 30. The springs 33 then draw the piston rod 17 of the catch mechanism back to its original position. As these parts approach their original position, the upwardly projecting finger is stopped by the stops 34 throwing the catch 25 upwardly in position to again engage the arm 18. The gun is now cocked and ready to fire. To fire the gun, the valve 10 is opened admitting compressed air from the reservoir 1 through the pipe 5 to the cylinder 6. The air admitted to the cylinder 6 forces outwardly the piston 48 and projecting parts 7 to actuate the trigger 8 and fire the gun.

Having now particularly described our invention we claim:—

1. Pneumatic cocking means for rapid firing small arms having a recoiling breech block and gun firing trigger, which comprises a pneumatic cylinder and piston, a valve to control the admission of air to said cylinder, a detent movable with said piston and a member extending from said breech block and engaged by said detent during the outward stroke of the piston, said detent being displaceable to release said member, a catch mounted on said detent and a spring actuated latch engaged by said catch to hold said catch and said recoil member at the end of the outward stroke of the piston.

2. Pneumatic cocking means for rapid firing small arms having a recoiling breech block and gun firing trigger, which comprises a pneumatic cylinder and piston, a valve to control the admission of air to said cylinder, a detent movable with said piston and a member extending from said

breech block and engaged by said detent during the outward stroke of the piston, said detent being displaceable to release said member, a catch mounted on said detent and a spring actuated latch engaged by said catch to hold said catch and said recoil member at the end of the outward stroke of the piston, pneumatically operated means for disengaging said latch from said catch and means for disengaging and moving said detent from the path of said breech block member from the recoil thereof.

3. Pneumatic cocking means for controlling rapid firing small arms having a recoiling breech block and gun firing trigger, which comprises a pneumatically operated cylinder and piston, a valve to admit air under pressure to said cylinder, a detent movable by said piston, a member extending from the recoiling breech block of said firearm to be engaged by said detent, said detent being displaceable to release said member, means for catching said detent at the end of its outward stroke and means comprising a fixed abutment for disengaging said catching means and disengaging and moving said detent from the recoil path of said breech block member.

4. Pneumatic cocking means for a machine gun having a cocking member extending therefrom, which comprises a pneumatic cylinder, a piston, a rod extending from said piston, a rocking member on said rod to engage said extending member and to move it with said piston, and a catch to engage and hold said rocking member and said extension at the outward stroke of the piston.

5. Pneumatic cocking means for a machine gun having a cocking member extending therefrom, which comprises a pneumatic cylinder, a piston, a rod extending from said piston, a rocking member on said rod to engage said extending member and to move it with said piston, a catch to engage and hold said rocking member and said extension at the outward stroke of the piston, and a pneumatically operated piston to engage and rock said rocking member to release said extension and said catch.

6. Pneumatic cocking means for a machine gun having a cocking member extending therefrom, which comprises a pneumatic cylinder, a piston, a rod extending from said piston, a rocking member on said rod to engage said extending member and to move it with said piston, a catch to engage and hold said rocking member and said extension at the outward stroke of the piston, a pneumatically operated piston to engage and rock said rocking member to release said extension and said catch, and means at the end of the return stroke to return said rocking member to its original position on said rod.

7. Pneumatic cocking means for machine guns having a cocking member extending therefrom, which comprises a pneumatically operated cylinder, a piston, a rod extending from said piston and bifurcated at its free end, a rocking member pivotally mounted in the bifurcated end of said piston and having a detent to engage said projecting member and move it with said piston, and also having a latch member, a spring operated latch to engage said latch member and hold said piston in its outermost movement, and means to rock said member to release said extension and said latch.
